(57) CLAIM

The ornamental design for a multi-function painter's tool, as shown and described.

DESCRIPTION

FIG. 1 is a top perspective view of a multi-function painter's tool showing my new design;

FIG. 2 is a right side elevation view thereof, the left side elevation being substantially a mirror image of this right side view;

FIG. 3 is a top plan view thereof;

FIG. 4 is a bottom plan view thereof;

FIG. 5 is a right end elevation view thereof;

FIG. 6 is a left end elevation view thereof; and,

FIG. 7 is a section view taken on the plane designated by the line labeled 7—7 of FIG. 3.
